Primary Examiner — Cynthia R Underwood(74) *Attorney, Agent, or Firm* — Abelman, Frayne & Schwab(57) **CLAIM**

The ornamental design for an over-the-door hanger, as shown and described.

DESCRIPTION

FIG. 1 is a top, front, left side perspective view of the over-the-door-hanger of my invention; FIG. 2 is a front elevation view thereof;

FIG. 3 is a rear elevation thereof;

FIG. 4 is a left side elevation thereof;

FIG. 5 is a right side elevation thereof;

FIG. 6 is a top plan view thereof;

FIG. 7 is a bottom plan view thereof;

FIG. 8 is a perspective view thereof, shown in an environment of use on the top edge of a door; and,

FIG. 9 is a perspective view thereof, shown in another environment of use supporting a closet organizer.

The broken lines form no part of the claim.
